DESIGN FOR A SEWING BOX

Herbert Jahn, Garfield, and Chester S. Zaremba,
Paterson, N. J., assignors to Cascade Plastics,
Inc., a corporation of New Jersey

Application February 4, 1947, Serial No. 136,670

Term of patent 14 years

(Cl. D3—19)

To all whom it may concern:

Be it known that we, Herbert Jahn and Chester S. Zaremba, citizens of the United States, residing at Garfield and Paterson, in the counties of Bergen and Passaic, respectively, and State of New Jersey, have invented a new, original, and ornamental Design for Sewing Boxes, of which the following is a specification, reference being had to the accompanying drawing, forming part thereof, wherein

Figure 1 is a perspective view of a sewing box showing our new design;

Figure 2 is a top plan view with the cover removed; and

Figure 3 is a sectional view taken on the line 3—3 of Figure 1.

We claim:

The ornamental design for a sewing box, as shown.

HERBERT JAHN.
CHESTER S. ZAREMBA.
